Des. 221,001

Patented June 29, 1971

221,001

ELECTRIC SOLDERING EQUIPMENT ANALYZER

Joseph A. Sylvester, Wayne, N.J., assignor to
Hexacon Electric Company

Filed Sept. 5, 1969, Ser. No. 19,035

Term of patent 14 years

Int. Cl. D10—10

U.S. Cl. D26—1

FIG. 1

FIG. 2

FIG. 3

FIG. 4

FIG. 1 is a perspective view of an electric soldering equipment analyzer with the cover in an open position showing my new design.

FIG. 2 is an elevational view of the left end of the electric soldering equipment analyzer, the right end being a mirror image thereof.

FIG. 3 is a plan view as seen from the top of FIG. 1; and FIG. 4 is a plan view as seen from the bottom of FIG. 1.

I claim:

The ornamental design for an electric soldering equipment analyzer, as shown and described.
